UNITED STATES PATENT OFFICE

FRANCIS X. MEEHAN, OF ST. LOUIS, MISSOURI, ASSIGNOR OF ONE-HALF TO ALFRED D. LUEHRMANN, OF ST. LOUIS, MISSOURI

EXERCISING BELT FOR MASSAGING MACHINES

Application filed July 19, 1928. Serial No. 293,803.

This invention relates to certain new and useful improvements in exercising or massaging machines, and has for its general object to provide means for decreasing the severity of the action of such machines without affecting the operation or changing the general character of the function performed by such machine.

There are various types of these machines on the market, but they are all characterized by the fact that two arms are rapidly reciprocated in alternation and a belt, usually constructed of canvas and having its ends secured to these arms, is applied to the body and rapidly drawn back and forth to produce a massaging effect upon the part of the body to which it is applied.

While many of these machines have adjustable means for either reducing or increasing the severity of the action of the belt, the adjustment of the machines is not always easy, especially for women, and cannot be effected while the machine is in use. Other makes of machines in quite general use have no means for adjusting the degree of the agitating action whatever.

Many persons have had operations of one kind or another performed on them, leaving the particular part of the body where the operation was performed very sensitive; or some part of the body may be sensitive due to some abnormal condition, and a massaging action of these machines that would be pleasant and stimulating at one part of the body will be too severe, and even painful, when applied at such a sensitive part of the body. In such cases, the one using the machine must either be content with a gentle action for the whole body, or must interrupt the treatment and adjust the machine to accommodate its motion to some sensitive part of the body.

The broad object of my invention is attained by using a belt which embodies in its structure means for absorbing, or minimizing, a part of the reciprocating or agitating motion of the machine, whereby to render the movement of the belt less abrupt and its action less severe in its effect upon the user.

With the above general object in view, my invention consists in providing an exercising belt for massaging or exercising machines capable of yielding when alternately pulled at its ends by the reciprocating arms of the machine.

Stated more in detail, my invention resides in providing an exercising belt having the property of elasticity, which may be effected by constructing the entire belt of rubber, or of any other elastic or resilient material, or by making a section of each end portion of the exercising belt of elastic or resilient material.

Belts constructed according to my invention may be readily substituted for the non-yielding or canvas belts generally employed, or in some embodiments of the invention, the resilient or elastic sections of the belt may be made removable and non-stretchable or non-elastic sections be inserted in their stead.

In the accompanying drawings—

Figure 1 is a plan view of an exercising belt having rubber loops;

Figure 2 is a view in side elevation of the same;

Figure 3 is a plan view of an exercising belt having rubber insert sections in its end portions;

Figure 4 is a view in side elevation of the same;

Figure 5 is a plan view on an enlarged scale showing an end of one of the sections of the belt shown in Figs. 3 and 4 provided with a retaining clip;

Figure 6 is a view in side elevation on an enlarged scale showing one of the rubber inserts used in the construction of the belt shown in Figs. 3 and 4;

Figure 7 is an enlarged sectional view on the line 7—7 of Fig. 4;

Figure 8 is a view in side elevation of a belt made entirely of rubber;

Figure 9 is a plan view of a belt having coil springs secured in its end portions;

Figure 10 is a view in side elevation of the same; and

Figure 11 is a view slightly in perspective showing the manner of using the belt illustrated in Figs. 1 and 2, which will serve as

illustrating the manner of using the other forms of the exercising belt shown.

Referring now to the drawings, the numeral 1 indicates one of the two hooks on the two arms of an exercising or massaging machine 2, on which hooks the end of a belt are adapted to be removably secured. To this end, each end of the belt is provided with a loop, which may be readily inserted over the hooks 1. When so applied and with the hooks 1 vibrating rapidly in alternation, the belt will be drawn rapidly back and forth on the body of the user, producing a more or less violent agitation of the body, depending upon the degree of severity of the vibrating action employed. For regulating the severity of the action of the exercising belt, I provide a belt having the quality of elasticity of resiliency.

Referring to Figs. 1 and 2, the belt is constructed of a canvas portion 3 having rubber loops 4 on its ends.

In Figs. 3 and 4, I show rubber sections 5, inserted and removably secured in the respective end portions of a canvas belt. To this end, the canvas end sections 6, extending from the leather loops 7, have secured on their ends retaining clips 8 (Fig. 5), providing recesses 9 closed at their bottoms and having a narrow slit or opening in their forward ends, as shown at 10, and a main section of canvas belt 11 has its opposite ends provided with similar clips 12 constructed in the same manner as the clips 8 shown in Fig. 5. Each of the rubber sections 5 has its ends provided with heads 13 adapted to fit snugly into the recesses of the respective sets of clips 8 and 12, as shown in Figs. 3 and 7. It will be readily understood that a similar section of non-stretchable material could be substituted at any time for the rubber sections referred to.

In Fig. 8, the entire belt 14, including the loops, is made of rubber, one of the loops being shown and indicated at 15.

In Figs. 9 and 10, the belt 16 is of canvas, and the holding loops 17, of leather. A series of coil springs 18 is inserted between each end of the canvas portion and a loop 17.

In all of the forms of the invention, it will be seen that in use, the pulling action of each of the hooks 1 will be partly absorbed by the resilient part of the belt and thus the degree of the agitating action on the body of the user, lessened. The user can, himself, readily increase the severity of this action by pressing his body more firmly against the belt to stretch it or extend its elastic sections, so that the belt, having a part of its elasticity already taken up, will respond more directly, or positively, to the agitating action of the movement of the hooks 1.

It will, of course, be apparent that belts having different degrees of elasticity or resiliency may be used and the character of the agitating action varied accordingly. For

example, if the rubber of which the belt is made, or the rubber sections thereof, or the coil springs, whichever are used, are of such strength as to yield only under great pressure, the degree of the agitating action will only be slightly decreased. If, on the other hand, rubber or springs that yield readily are employed, the degree of agitating action will be decreased to a greater extent for a given degree of pressure of the body on the belt.

The illustrated embodiments of my invention are not intended as exclusive, as I realize that various modifications may be made in the construction of such a belt as I contemplate without departing from the broad idea of my invention as embodied in the claim.

I claim:

An exercising belt for massaging machines having a main section provided at each of its ends with a retaining device, end sections each of which has at its outer end a unitary engaging member and at its inner end a retaining device, and rubber belt sections having their opposite ends secured, respectively, in the corresponding retaining devices of said main and end sections.

In testimony whereof, I have hereunto set my hand.

FRANCIS X. MEEHAN.
